UNITED STATES PATENT OFFICE

2,147,869

DISPLAY STAND

George F. Wales, Buffalo, N. Y., assignor to American Radiator Company, New York, N. Y., a corporation of New Jersey

Application April 2, 1938, Serial No. 199,615

4 Claims. (Cl. 40—68)

My invention relates to display apparatus and the same has for its object to provide a simple, efficient and inexpensive apparatus for supporting and displaying a number of signs or cards in such manner as to render the same readily observable.

Further, said invention has for its object to provide an apparatus of the character specified in which a number of signs or cards having descriptive matter or titles may be readily inserted into and removed therefrom.

Further, said invention has for its object to provide a revoluble holder having a plurality of side walls, and means on said side walls for receiving and retaining signs or cards therein.

Further, said invention has for its object to provide a holder having convex side walls, and card or sign receiving means conformed to said convex side walls in order to maintain the card or signs in position therein by frictional engagement due to the flexing of the cards or signs.

Other objects will in part be obvious and in part be pointed out hereinafter.

To the attainment of the aforesaid objects and ends my invention consists in the novel features of construction, and in the combination, connection and arrangement of parts hereinafter more fully described and then pointed out in the claims.

In the accompanying drawings—

Figure 1 is a perspective view showing one form of display apparatus constructed according to and embodying my said invention;

Fig. 2 is a side elevation partly broken away and in section;

Fig. 3 is a transverse section on the line 3—3 of Fig. 2;

Fig. 4 is an elevation of one of the card or sign frames;

Fig. 5 is a side edge view thereof;

Fig. 6 is a top edge view thereof;

Fig. 7 is a detail sectional view illustrating the shaft or post bearing at the upper end of the apparatus;

Fig. 8 is a similar view illustrating the bearing at the base of the apparatus, and

Fig. 9 is an enlarged detail sectional view on the line 9—9 of Fig. 1.

In said drawings 10 designates a display apparatus comprising a hollow, metal shell or drum 11 having a plurality of convex side walls 12. In the present instance the shell, by preference, is shown as of substantially triangular form in cross section, but it will be understood that any number of side walls may be employed.

The shell 11 is formed with open top and bot-

tom ends, and is provided at its upper end with a spider frame 13 formed of sheet metal comprising a substantially-triangular flanged rim 13a and a centrally-located hub 14 connected to said flanged rim 13a by integral arms 15. The hub 14 is struck up from the metal of the spider and includes an inwardly-inclined, upwardly-extending portion 16, and a downwardly-inclined, inwardly-extending portion 17 having an opening 18 at its base.

The lower part of the shell or drum 11 is provided with a sheet metal base 19 of substantially-triangular outline having a flanged rim 20 and a centrally located hub 21 struck up from said base. The hub 21 includes a downwardly and inwardly-extending portion 23 terminating in an upwardly and inwardly-extending portion 24 having an opening 25.

26 denotes a tubular shaft extending through the openings 18, 25 in the upper and lower hubs 20 and 21. The lower end of said tubular shaft is provided with a threaded portion 27 to receive a nut 28 whereby the shaft may be secured to a suitable rigid support as 29. Above the threaded portion of said shaft 26 is secured a collar 30 having a beveled upper end 31 adapted to revolvably engage with the upwardly and inwardly-inclined portion 24 of the hub 21. The upper end of the shaft 26, which extends through the opening 18 in the upper spider frame 13, is threaded and provided with a knurled, adjustable cone bearing 32 having an interiorly-threaded upper end to receive a threaded locking plug 33 which serves to hold the shell or drum 11 duly in position upon the shaft 26.

34 denotes card or sign frames which are severally substantially coextensive in size with the side walls 12 of the shell or drum 11. Each frame 34 is struck up from a sheet of metal to form a series of wide, parallel projections 35, extending transversely of the frame, and separated from each other by a series of relatively narrow, transverse projections 36. The wide projections 35 extend outwardly and have cut-out portions or windows 37, and the narrow projections 36 extend in the reverse direction. The frames 34 are of convex form and conform to the outer surfaces of the convex side walls 12 of the shell or drum 11 and are secured thereto along their edges by screws or other fastening means. The rearwardly extending narrow projections at the upper and lower ends of the frames form flanges 38, 39, respectively contacting with the convex side walls 12 adjacent the upper and lower ends of the shell or drum.

40 denotes a dome-shape cover which encloses the open upper end of the shell or drum 11.

The wider outwardly-extending projections of the frame 34 form recesses into which are inserted endwise cards or signs 41, bearing any desired titles or inscriptions, which cards are frictionally held in position therein.

It will be noted that the invention provides a simple and efficient display apparatus in which the cards or signs may be readily inserted and removed from either end, and in which the cards or signs are firmly held in position by the flexing of the same in conforming the same to the curvature of the side walls of the shell or drum and to the frame members secured thereto.

Having thus described my said invention what I claim and desire to secure by Letters Patent is:

1. An apparatus of the character described comprising a support, a member revolvably mounted upon said support and having a plurality of side walls, and frames each formed as an integral structure of a sheet of metal corresponding in outline generally with one of said sides and secured thereto, said frames each having alternate outwardly and inwardly projected transverse portions, and said outwardly projected portions forming a series of parallel, superposed sign-receiving compartments.

2. An apparatus of the character described comprising a support, a member revolvably mounted upon said support and having a plurality of side walls, and frames each formed as an integral structure of sheet metal corresponding in outline generally with one of said side walls and secured thereto, said frames each having alternate wide and narrow outwardly and inwardly-projected horizontal portions, and said narrow, inwardly-projected portions constituting spacing members between said wide outwardly-projected portions; said outwardly-projected portions forming a series of parallel, superposed, sign-receiving compartments having openings

therein to expose the signs disposed in said outwardly-projected portions.

3. An apparatus of the character described comprising a support, a member revolvably mounted upon said support and having a plurality of convex side walls, and transversely curved frames each formed as an integral structure of sheet metal corresponding in outline generally with one of said side walls and conformed and secured thereto along its vertical edges, said frames each having alternate wide and narrow outwardly and inwardly-projected horizontal portions, and said narrow, inwardly-projected portions constituting spacing members between said wide outwardly-projected portions; said outwardly projected portions forming a series of parallel, superposed, sign-receiving compartments having openings therein to expose the signs disposed in said outwardly-projected portions.

4. An apparatus of the character described comprising a hollow member, bearings within said member adjacent its upper and lower ends, a post received by said bearings for revolvably supporting said hollow member, said hollow member having a plurality of convex sides, a cover closing the top of said hollow member, and frames each formed as an integral structure of sheet metal corresponding in outline generally with one of said convex sides and transversely curved to correspond to its respective side and secured thereto along its vertical edges, said frames having wide horizontal outwardly-projected portions separated from each other by relatively narrow spacing portions, said outwardly-projected portions forming a series of parallel, superposed sign-receiving compartments open at their opposite ends, and having openings therein intermediate said ends to expose the signs disposed within said compartments.

GEORGE F. WALES.
